POWER DRIVEN VEHICLE TOY

Arthur W. Swenson, Rockford, Ill.

Application August 31, 1938, Serial No. 227,647

12 Claims. (Cl. 46—213)

This invention relates to improvements in power propelled toy vehicles such as automobiles, trucks, boats, and the like, and more particularly to toys of the character in which the 5 vehicle movements are controlled by cam means shaped according to the path to be traversed by the vehicle.

One object is to provide a toy vehicle of the above character having mechanism for controlling 10 selectively the functions of starting, stopping, forward advance, reverse and steering, as well as for correlating these functions with each other so that the vehicle may be caused to traverse a wide variety of paths predetermined by the 15 shape of the cam mechanism.

Another object is to provide a novel vehicle toy having a cam actuated clutch mechanism for controlling the starting, stopping, and direction of advance.

20 Still another object is to provide a spring actuated toy vehicle having a novel speed reducing mechanism.

A further object is to provide a novel toy truck embodying mechanism for dumping the truck 25 body automatically.

The invention also resides in the novel structural character of the steering mechanism and the direction control clutch.

Other objects and advantages of the invention 30 will become apparent from the following detailed description taken in connection with the accompanying drawings, in which

Figure 1 is a plan view of the chassis of a toy automobile embodying the novel features of the 35 present invention.

Figs. 2 and 3 are fragmentary sectional views taken respectively along the lines 2—2 and 3—3 of Fig. 1.

Fig. 4 is an enlarged view of a portion of Fig. 1 40 showing a portion of the speed reducing mechanism.

Fig. 5 is an underside view.

Figs. 6, 8, and 10 are diagrammatic views showing the paths traversed by the vehicle when controlled by cams of the shapes shown in Figs. 5, 45 7, and 9, respectively.

Figs. 7 and 9 show different form of cams.

Fig. 11 is an elevational view partially in section of a toy dump truck embodying the invention. 50

Fig. 12 is a section taken along the line 12—12 of Fig. 11.

Fig. 13 is a fragmentary bottom view of the dump truck.

55 For purposes of illustration, the invention has

been shown in the drawings and will be described herein as a toy automotive vehicle. It is to be understood that I do not intend to limit the invention by such disclosure but aim to cover all other modifications and adaptations falling 5 within the spirit and scope of the invention as expressed in the appended claims.

In the drawings, 13 indicates the automobile frame which is punched out of sheet metal, properly bent to impart the required rigidity, and 10 provided with means for attachment of a vehicle body 12. The front wheels 14, which are suitably surfaced to reduce skidding, rotate on the ends of arms 15 hinged intermediate their ends on vertical pivot pins 16 on the frame. The 15 inner ends of the arms are joined by pin and slot connections 17 to the outer ends of a horizontally swingable lever 18 pivoted at its center on a stud 19. At the forward end, the frame is cut away as indicated at 20 to permit the wheels 20 to be swung from the extreme right turn position (Fig. 1) to an extreme left turn position.

The rear wheels 21 are fast on an axle 22 journaled at opposite ends in flanges 23. For a purpose to appear later, the axle and the wheels are 25 shiftable bodily in an axial direction.

Power for propelling the vehicle and for actuating the steering mechanism is, in the present instance, derived from a motor comprising a spiral spring 24 having one end anchored to the chassis and the other end connected to a vertical shaft 25. The latter is journaled at opposite ends between auxiliary frames 26 and 26^a, and may be turned to wind up the spring by a key 27 coupled to the upper end of the shaft. Through 30 the usual pawl and ratchet connection (not shown), the shaft 25 is coupled to a gear 28^a meshing with a pinion 29^a which is rigid with a crown gear 30. The studs carrying the various pinions and gears are mounted on the frame 35 plate 13 and held in place by the auxiliary frame member 26. The gear 30 meshes with a pinion 31 on a propeller shaft 32 having its forward end 33 journaled in the auxiliary frame 26 and its rear end rotatably supported in lug 33^a integral 45 with and upstanding from the frame 13.

Fast on the rear end of the shaft 32 is a pinion 34 disposed between two crown gears 35 and 36 having hubs 37 fast on the axle 22 and teeth projecting toward each other for engagement 50 with the pinion. When the pinion is in mesh with the gear 36 as shown in Figs. 1 and 5, the vehicle will be propelled reversely. Forward advance occurs when the pinion meshes with the gear 35. When the pinion is disengaged from 55

both gears, it rotates idly and the vehicle remains at rest.

The pinion 34 and the gears 35 form a simple clutch mechanism by which the starting, the stopping, and the direction of advance of the vehicle may be controlled. Selective engagement and disengagement of the clutches is effected in the present instance by bodily shifting the axle 22 and the rear wheels. For this purpose, 10 a lever 38 (Fig. 5) is extended longitudinally of the chassis on the under side of the frame plate and pivoted intermediate its ends on a stud 39. The rear end 40 of the lever is bent upwardly and disposed between the crown gear hubs 37 which form a clutch collar.

15 The forward end 41 of the clutch lever constitutes a follower for an open face cam 42 which preferably comprises a flat metal disk having the desired peripheral contour. The cam is carried 20 on the squared lower end 43 of a vertical shaft 44, and is detachably held thereon by any suitable means such as a thumb nut 45. Fast on the upper end of the shaft is a gear 51 meshing with a pinion 28 which rotates with the gear 29. With 25 this arrangement, the cam shaft is driven at a very low speed as compared to the speed of rotation of the drive wheels 21.

A spring 46 stretched between the frame 13 and the lever 38 holds the follower against the cam 30 and shifts the lever in one direction as permitted by the contour of the cam. When the follower engages a raised surface 47 of the cam, the lever 38 and the rear axle 22 are shifted against the action of the spring 46 to engage the pinion 34 35 and the gear 36 thereby conditioning the clutches for reverse movement of the vehicle. During engagement of the follower and a depressed surface 48, the gear 35 is shifted into engagement with the drive pinion and the vehicle is propelled forwardly. The shift from forward to reverse and vice versa occurs as the follower encounters rises and falls 49 and 50.

The invention contemplates actuation of the steering mechanism in timed relation to actuation of the clutch mechanism above described 45 so as to cause the vehicle to traverse any selected path. This is accomplished through the medium of an open face cam 52 received on the squared end of the shaft 44 adjacent the cam 42 and 50 acting on a follower in the form of a stud 53 rigid with a rearwardly projecting arm 54 on the steering lever 18. The stud projects downwardly through an arcuate slot 55 in the frame 13 and is held against the cam periphery by a spring 56. 55 While the follower 53 is bearing against a raised surface 57 of the cam 52, the bell crank lever 18 is swung against the action of the spring 56 to the extreme right turn position of the front wheels. The wheels are held in the extreme left 60 turn position when the follower engages the surface 58. Any intermediate position between these extremes may be produced by proper shaping of the cam 52. For example, the vehicle may move straight forward or backward while the follower 65 53 rides along a surface 60 (Fig. 7).

By mounting the front wheels on the individual levers 15 actuated by a common bell crank 18, the required swinging movement of the front wheels may be obtained without the necessity of enlarging the cam 52 to an objectionable degree. This is because the ratios of levers 15 and 18 may be varied as desired to produce the requisite movement of the wheels for a given movement of the cam follower.

70 Preferably, though not necessarily, the two

cams 42 and 52 are fastened rigidly together so as to maintain the fixed angular relation required for causing the vehicle to traverse the intended path when under their control. By removing the thumb screw 45, the cams may be removed and 5 replaced by other cams such as those shown in Figs. 7 and 9 which may be shaped to produce any desired path of vehicle movement. The cams are of simple construction and easy to replace so that a wide variety of predetermined vehicle 10 movements may be obtained at a low cost thereby increasing materially the utility of the toy.

A simple and inexpensive means is provided for slowing down the speed of operation of the spring motor. This means comprises a gear 29 15 (Fig. 1) meshing with the pinion 28 and with a pinion 61 rigid with a gear 62 which in turn meshes with a pinion 63 loose on a stud 64 and rigid with a gear 65. The number of teeth on the latter gear is one less than on a gear 66 also 20 loose on the stud. Both gears 65 and 66 mesh with a gear 67 journaled on a stud 68. With this arrangement, additional friction is imposed on the spring motor effectually preventing it from attaining an objectionably high speed. 25 Starting and stopping of the spring motor may be controlled by a manually shiftable lever 69 pivoted on the frame 13 and having an end 70 movable into and out of blocking engagement with the teeth of the gear 67.

30 The action of the toy with cams of the shape shown in Fig. 5 is illustrated in Fig. 6. Starting from the position shown in full outline, the followers 41 and 53 engage the cams 42 and 52 to hold the front wheels in the right turn position with the gear 36 shifted into engagement with drive pinion 34. When the motor is started, the vehicle moves backward and to the left along the line 71, the cam shaft 44 rotating in the direction indicated by the arrow (Fig. 5). After 40 the vehicle has described nearly a complete circle, the cam surface 50 is presented to the follower 41 causing the rear axle to be shifted in a direction to disengage the gear 36 from the pinion and engage the gear 35. This interrupts the backward 45 movement and initiates forward advance of the vehicle. Simultaneously, the follower 53 rides off from the surface 57 onto the surface 58 which results in shifting of the front wheels from the right to the extreme left turn position. As a result, the vehicle is propelled forwardly along the circular path 72. At the point 73, the initial condition of the steering and clutch mechanism is restored whereupon the vehicle proceeds backwardly along the line 74. Finally, at the point 75, 55 the cams shift the front wheels to the left and engage the forward clutch so that the vehicle returns to the starting position along the line 76. Thus, in each two revolutions of the cam shaft, the vehicle traverses a path corresponding to the 60 outline of a four leaf clover.

55 While in the example described the vehicle was started from the position shown in Fig. 5, it is obvious that the same may be started at any other position. For instance, with the cams in 65 the position they would occupy at point 75, the vehicle would start out in a forward direction and continue around the same course.

By substituting for the cams 42 and 52, cams 42' and 52' of the shape shown in Fig. 7, an entirely different path of movement illustrated in Fig. 8 may be obtained. With the followers engaging the cams as shown, the vehicle starts forward in a straight line 77 from the position shown in full outline. At the point 78, the gear 35 dis- 70 75

engages the pinion 34 and the vehicle dwells while the gear 36 is being shifted into mesh, the front wheels being shifted to the right turn position. Then, the vehicle proceeds backward along the 5 curved path 79. At 80, the direction is reverse and the wheels turned left so that a curved path 81 is traversed. After moving through more than a complete circle, the vehicle stops at 82, reverses along a curve 83, and finally moves forwardly along a straight line 84 back to the starting point. Completion of this path requires one revolution of the cam shaft.

The path of movement of a vehicle (see Fig. 10) in backing up to turn around and advance 15 forwardly but in the reverse direction will be traversed under the control of cams 42" and 52". Starting with the cams positioned as shown in Fig. 9 and with the vehicle in the full line position (Fig. 10) it first moves forwardly to the 20 point 86, then backwardly to the point 87 where it will stop temporarily while both gears 35 and 36 are held out of mesh with the pinion 34 as will be the case while the follower 41 is engaging the surface 41a. The steering and clutch 25 mechanisms are actuated at this point to initiate forward advance to the left around the curve 88 whereupon the front wheels are straightened to cause a straight line advance 89.

By synchronizing the actuations of the steering 30 and clutch mechanisms as by the use of cams on a common shaft, the path of movement of the vehicle in one cycle is definitely predetermined and such paths are accurately duplicated in repeated cycles. Thus, by shaping the cam surfaces to 35 properly correlate the steering, stopping, starting, and direction of advance, any desired path of movement may be obtained. If desired, suitable indicia such as an arrow 90 may be formed on the cam 52 to indicate the normal position relative 40 to the follower 53 from which the cam should be started in order to describe the intended path.

Provision may also be made for performing other functions automatically in timed relation to movements of the vehicle. Figs. 11 to 13 illustrate an arrangement for dumping a truck having a box or dump body 91 for containing material hinged on a pivot pin 92 supported above and ahead of the axle by the flanges 23 at the sides of the frame plate 13. The pivot is so located 50 relative to the center of gravity of the box when loaded that it will tend to swing into the dumped position shown in dotted outline under the weight of the material carried in the box, the floor of the latter being inclined as indicated at 55 95 to induce a flow of material toward the rear end of the box. A yieldable arm 93 depending from the forward end of the box 91 projects through an opening 94 in the frame 13 when the box is in its lower normal position, a shoulder 60 96 on the arm engaging the under side of the frame to latch the box in normal position.

The latch 93 is tripped automatically at a pre-determined point in the revolution of the cam shaft 44. This may be accomplished by (Fig. 11) 65 a horizontally swingable lever 97 pivoted at 98 on the frame 13 with one end 99 disposed adjacent the latch 93 but held in inactive position by a spring 100. The other end 101 of the lever constitutes the follower of a cam 102 fast on the 70 shaft 44 and having a lobe 103 positioned to engage the follower at the point in the vehicle cycle at which it is desired to dump the body 91. Upon such engagement, the lever 97 is swung against the latch to release the shoulder 95 thereby permitting the body to tilt under the over-balanced 75

weight of its contents. As the body reaches the position shown in dotted outline (Fig. 11), an arm 104 engages the frame 13 releasing a latch 105 to permit a gate 106 at the rear end of the body to swing open. The contents may then slide 5 out of the tilted body.

As an incident to such tilting of the dump body, a contractile spring 107 extending between the forward end of the flat portion of the body 91 and the truck cab 108 becomes tensioned sufficiently to induce reverse tilting of the dump body as soon as the body has been emptied. The body is thus returned to normal position and the gate 106 is automatically closed.

Instead of employing a separate cam 102, the 15 latch 93 may be released by cam means formed on one of the cams 42 and 52. Thus, as shown in Fig. 9, the lever 97 may be actuated by a lug 109 formed at the proper point on the cam 52.

By timing the dumping operation with the vehicle movements, the operation of a commercial truck may be closely simulated. For example, with cams constructed as shown in Fig. 9, the trip lever would preferably be actuated by the lug 109 while the vehicle is dwelling in its back-up 25 position at the point 87.

I claim as my invention:

1. A toy vehicle having, in combination, a motor carried by the vehicle, mechanism for steering the vehicle, drive mechanism selectively operable to cause movement of the vehicle in opposite directions by said motor, and means driven by said motor and operable to actuate said steering and drive mechanisms in timed relation whereby to cause the vehicle to traverse a pre-determined path under the power of said motor.

2. A toy vehicle having, in combination, a motor carried by the vehicle, mechanism for steering the vehicle, drive mechanism selectively operable to impart propelling power from said motor to the vehicle or to interrupt the application of such power, and means driven by said motor and operating said steering and drive mechanisms selectively and in timed relation to each other.

3. A toy vehicle having, in combination, a power driven motor carried by the vehicle, drive mechanism for propelling the vehicle, clutches respectively operable to connect said motor and said drive mechanism for propulsion of the vehicle in opposite directions, mechanism for steering the vehicle, a cam shaft driven by said motor and having two cams thereon rotatable in unison, followers for said cams, and means actuated by said follower and respectively operating to variably actuate said steering mechanism and selectively engage said clutches.

4. A toy vehicle having, in combination, a motor carried by the vehicle, mechanism for steering the vehicle, drive mechanism selectively operable to impart power from said motor to the vehicle to propel the latter, a cam shaft continuously driven by the motor during operation thereof, two cams removably mounted on said shaft for rotation therewith, means detachably securing said cams on the shaft to permit of ready removal and replacement by differently shaped cams, and means actuated by the respective cams for actuating said steering and drive mechanisms selectively.

5. A toy automotive vehicle having, in combination, a chassis having wheels thereon swingable laterally to steer the vehicle, a motor carried by said chassis, drive mechanism selectively operable to connect said motor to and disconnect the same from wheels of said chassis.

- whereby to control propulsion of the vehicle under the power of said motor, and cam mechanism continuously operated during operation of said motor and operable to variably position said first mentioned wheels and render said drive mechanism operative selectively whereby to cause the vehicle to traverse a path predetermined by the contour of said cam mechanism.
6. A toy vehicle having, in combination, a 10 motor carried by the vehicle, means driven by said motor for propelling the vehicle including clutch mechanism selectively operable to cause starting, stopping, and forward or reverse movements of the vehicle under the power of said 15 motor, a rotary cam driven by said motor, and means controlled by said cam and selectively controlling said clutch mechanism.
7. A toy vehicle having, in combination, a 20 motor carried by the vehicle, means driven by said motor for propelling the vehicle including a selectively operable reversing clutch, and mechanism driven continuously during operation of said motor and operable to actuate said clutch selectively and cause the vehicle to traverse a 25 predetermined sequence of forward and reverse movements respectively having predetermined lengths.
8. A toy vehicle having, in combination, a 30 frame, a drive shaft rotatably mounted on said frame, a motor carried by said frame, two gears coupled to said drive shaft and spaced therealong with their teeth projecting toward each other, a propeller shaft driven by said motor, a pinion on said propeller shaft disposed between 35 said gears and selectively engageable with the teeth thereof, a rotary cam driven by said motor, and mechanism actuated by said cam and operable to effect relative movement between said pinion and said gears in a direction axially 40 of said drive shaft to bring one or the other of the gears into mesh with the pinion.
9. A toy vehicle having, in combination, a

frame, a rotary drive member for propelling the vehicle, a spring motor on said frame, a gear train for transmitting rotary power from said motor to said driven member, a spur gear driven from an element of said gear train, a second 5 spur gear rotatable on the axis of said first gear and having a different number of teeth than the first gear, and an idler gear meshing with the teeth of both of said spur gears.

10. A toy vehicle having, in combination, a 10 wheeled frame, a dump body pivoted on said frame to over-balance under the weight of material in the body whereby to dump automatically, a latch operating to hold said body in normal position, a motor actuated cam, and means 15 actuated by said cam to release said latch and permit dumping of said body.

11. A toy vehicle having, in combination, a 20 wheeled frame, a dump body pivoted on said frame to over-balance under the weight of material 25 in the body whereby to dump automatically, a latch operating to hold said body in normal position, a motor actuated cam, means actuated by said cam to release said latch and permit dumping of said body, a gate at the rear of said 25 body, a latch normally holding said gate closed, and means operating as an incident to dumping of said body to release said gate latch and permit opening of the gate.

12. A toy vehicle having, in combination, a 30 wheeled frame, a dump body movably mounted on said frame and normally tending to move the dumping position under the weight of material in the body, said body when emptied tending to move automatically back to normal position, 35 means releasably holding the body in said normal position, motor driven mechanism on said frame, and means actuated by said mechanism to release said body for movement to dumping position.

ARTHUR W. SWENSON.
